UNITED STATES PATENT OFFICE.

EDGAR C. BISBEE, OF MINNEAPOLIS, MINNESOTA, ASSIGNOR OF ONE-HALF
TO CHARLES F. ELMES, OF COOK COUNTY, ILLINOIS.

OIL-CAKE-STRIPPING MACHINE.

SPECIFICATION forming part of Letters Patent No. 739,479, dated September 22, 1903.

Application filed June 6, 1901. Renewed February 24, 1903. Serial No. 144,833. (No model.)

To all whom it may concern:

Be it known that I, EDGAR C. BISBEE, a citizen of the United States, residing in Minneapolis, in the county of Hennepin and State of Minnesota, have invented certain new and useful Improvements in Oil-Cake-Stripping Machines, of which the following is a specification.

My invention relates to improvements in oil-cake-stripping machines, and is adapted to strip cloth from the cakes of oil-meal, eject the cakes from the press-truck, and remove the press-plates as each cake is ejected.

This machine is adapted to operate in conjunction with the machines described in my applications for Letters Patent, Serial No. 63,362, filed June 6, 1901, for an oil-cake-forming apparatus, and Serial No. 65,090, filed June 19, 1901, for an oil-cake press.

In the accompanying drawings, forming part of this specification, Figure 1 is a side elevation of my improved oil-cake-stripping machine, portions of the frame being shown broken away to expose the working parts more clearly to view. Fig. 2 is a plan view of my invention. Fig. 3 is a longitudinal section taken on the line X X of Fig. 2. Fig. 4 is a similar section showing the carrier forward. Fig. 5 is a detail section taken on the same line, showing the carrier returning. Fig. 6 is a view looking toward one end of the machine, and Fig. 7 is a view looking toward its other end.

In the drawings let A represent the frame of the oil-cake-stripping machine; B, the truck for holding the oil-cakes to be stripped; C, the truck for receiving the press-plates as they are removed from the oil-cakes; D, the ejecting mechanism; E, the cloth-take-up mechanism; and F the drive mechanism for operating the parts of the machine. The trucks B and C are of substantially the same construction described in the applications for patents referred to above. The truck C, which has been emptied in the cake-forming apparatus, is rolled on the track 2 into one end of the frame A, where it is locked by the cross-bar 3. The truck B is rolled into the other end of the frame on the same track and is also locked in the frame by the bar 4.

This truck is loaded with cakes having press-plates between and cloth wrapped around each cake, (shown in the drawings,) as received from the oil-cake press after the oil has been extracted from the meal. 55

The ejecting mechanism D consists of the carriage 5, which slides backward and forward in the slots 6 of the longitudinal bars 7 of the frame. The carriage is operated by means of the bracket 8, attached to the carriage by bolts 9 and formed with the vertical slot 10. The pairs of sprocket-wheels 11 and 12 are arranged and journaled by their respective shafts 13 and 14 on the frame A, as shown in Fig. 2. The sprocket-chains 15 and 16 travel on these sprocket-wheels and carry the drive-bar G, which passes freely through the slot in the bracket of the carriage. When revolving in the direction of the arrows shown in Fig. 1, this drive-bar reciprocates 60 the carriage over the trucks. The carriage has the ejector I, attached by the supporting-bars 17. This ejector is arranged horizontally in the frame and is made concave at 18 to engage the top cake of the stack J when 65 moving forward and with the shoulder 19 to engage the top plate on the stack when moving backward. The pair of shafts 13 carry the sprockets 20, which are connected to the drive-shaft and pulley 21 and 22 by the chains 70 23 and sprockets 24. The drive-shaft is journaled at 25 on the frame of the machine. 75

The cloth-take-up mechanism consists of the cloth-roller 26, which is journaled in the arms 27 of the truck C. This roller carries 80 the pinion 28, which meshes with the gear 29. The shaft 30, which is journaled at 31 on the frame, carries this gear, also the disk 32, with the spring-dog 33 upon its face. This dog is adapted to engage the teeth of the ratchet-wheel 34 when the shaft 36 is revolving forward, as indicated by the arrow in Fig. 1. The shaft 35 is journaled at 36 on the frame and carries the drum 37, to which the weighted cable 38 is attached. This shaft also carries 85 the gear 39, which meshes with the rack 40. This rack slides in the bearings 40' and is formed with the shoulder 41, against which the arm 42 on the carriage is adapted to impinge when the carriage is moving forward. 90 95 100

As the rack is moved forward by the carriage the shaft 35 is revolved backward by means of the gear 39, and the cable 38 is wound upon the drum 37 by the movement of the rack. The spring-dog 33 then sweeps over the ratchet-wheel 34. As the carriage returns the weighted cable revolves the shaft 35 forward and the dog engages the ratchet-wheel, thus causing the cloth R to wrap upon the revolving roller 26 in the direction indicated by the arrows. The rack is returned by the weighted cable until the cloth has been stripped from the cake last ejected and wound upon the roller. The arm 42 continues the return stroke from the shoulder until the carriage has receded and started on a new stroke. This construction compensates for the varying difference between the travel of the carriage and the diameter of the roll of cloth, which latter is constantly increasing as the cloth is stripped from the cakes. The cloth travels over the idle roll 43 and between the pair of idle rolls 44, all of which are journaled and arranged in the frame, as shown in the drawings.

The method of regulating the height of the stack of cakes J and the plates K is substantially the same as described in my application for Letters Patent for oil-cake-forming apparatus above referred to, in which the mechanism L for adjusting the stack of cakes is termed the "cake-holding" mechanism and the mechanism M for receiving the press-plates the "press-plate-holding" mechanism.

The cake-holding mechanism consists of the truck B, which is journaled on the wheels 45 and limited in its forward and backward movement in the machine by the stop 46 and removable cross-bar 4. The stack of cakes wrapped in cloth and separated by press-plates as received from the oil-press is adapted to rest upon the shoulders 47 of the truck B. (See Fig. 6.) The head 48 is raised one step—i. e., the thickness of the cake plus that of the press-plate and cloth wrapped around the cake—during each full stroke of the carriage, so as to feed a cake and press-plate to the ejector. The head is moved by its vertical rack 49, which slides vertically in the guide 50 and meshes with the pinion 51. (Shown in Fig. 6.) This pinion is journaled by the shaft 52 on the frame, which also carries the sprocket 53.

The press-plate-receiving mechanism M consists of the truck C and the rack 55, having the head 56. This rack slides in the guide 56' and meshes with the pinion 57 on the shaft 58, which carries the sprocket 54. The sprockets 53 and 54 are adapted to revolve in the direction of the arrows shown in Fig. 1 by the sprocket 59 and chain 60. The relative sizes of the sprockets 53 and 54 are such as to raise the head 48 the thickness of the cake, press-plate, and double thickness of the cloth, while the head 56 lowers the thickness of one press-plate. This simultaneous rais-

ing and lowering of the heads is for the purpose of ejecting and stripping one cake at each forward movement and removing a plate to the press-truck C at each return movement of the ejector. The sprocket 59 is mounted on the drive-shaft 61, which carries the drive-sprocket N. This drive-sprocket is revolved the distance between its teeth by the drive-bar G each time the chains 15 and 16 make a complete revolution. I have arranged two ratchet-escapements P and Q upon the shaft 61. The ratchet P consists of the toothed wheel 62 and dog 63 and prevents the backward revolution of the shaft 80 by the weight of the cakes on the head 48. The ratchet Q consists of a ratchet-wheel 64 and dog 65, which is directed against its teeth so as to prevent the forward movement of the shaft except when the drive-bar G trips the dog from engagement with the teeth by its depending arm 66 and revolves the drive-sprocket.

In operation the drive-bar is revolved continually in the direction of the arrows by the drive-pulley 22. The strokes of the drive-bar cause the reciprocating movement of the carriage over the trucks. Assuming the carriage to be starting from the position shown in Fig. 1, the drive-bar trips the dog 65 and revolves the drive-sprocket one tooth forward, thus raising the head 48 the thickness of a cake plus that of a press-plate and the double thickness of the cloth to the position shown in Fig. 3 and also dropping the head 56 the thickness of one press-plate. The carriage then moves forward and the ejector engages the cake 67 and slides it forward onto the receiver 68 to the position indicated in Fig. 4. During this movement the cloth is stripped from the cake and the carriage-arm, impinging against the shoulder 41, slides the rack forward, thus winding the weighted cord onto the drum. During the return stroke of the carriage the shoulder 19 of the ejector engages the plate 69, as shown in Fig. 5, and removes the plate to the receiving mechanism, as shown in Fig. 1. The weighted cable also revolves the shaft 35, which causes the cloth stripped from the cake to wrap upon the roll 26 while the ejector is returning. This operation is repeated until all of the cakes on the truck B have been stripped and ejected and the plates removed and stacked onto the truck C. When completed the press-plates rest upon the top of the truck and the head 56 is free. The bars 3 and 4 are then removed and the trucks rolled from the frame to the cake-forming machine. The cakes of meal as ejected from the truck and stripped of cloth may be carried from the receiver by hand or by an endless carrier. (Not shown.)

Having described my invention, what I claim as new, and desire to protect by Letters Patent, is—

1. An oil-cake-stripping machine, comprising in combination, mechanism for holding

oil-cakes having press-plates between them and cloth wrapped around each cake, means for ejecting the cakes and removing the plates, and a device for stripping and winding the cloth.

5 2. An oil-cake-stripping machine, comprising in combination, a supporting-frame for a series of press-plates having cakes between them, a carriage adapted to reciprocate above said frame, an ejector, carried by said carriage, adapted to remove a cake from said frame during its forward movement and a plate during its return movement, and drive mechanism for operating said carriage.

15 3. An oil-cake-stripping machine, comprising in combination, mechanism for holding cakes having press-plates between them and cloth wrapped around each cake, and mechanism for removing said plates, ejecting said cakes and stripping the cloth simultaneously.

25 4. A machine of the class described, comprising in combination, means for holding a stack of press-plates, each carrying an oil-meal cake wrapped in cloth, and mechanism for removing each cake from the plate which it rests upon, stripping the cloth therefrom and removing said plate from said stack.

30 5. An oil-cake-stripping machine, comprising in combination with a holder for a stack of cakes, press-plates between the cakes and cloth wrapped around the cakes, mechanism for ejecting said cakes, stripping the cloth and removing the cakes from the stack.

35 6. A machine of the class described, comprising in combination with a holder for a stack of press-plates having cakes between them and cloth wrapped around each cake, reciprocating mechanism adapted to eject the cakes from the stack and strip the cloth from the cakes, and means for removing a plate after each cake is ejected.

40 7. An oil-meal-cake-stripping machine, comprising in combination, a holder for a stack of press-plates having cakes between them, a reciprocating ejector adapted to eject a cake during one movement, and remove a plate during its alternating movement.

45 8. An oil-meal-cake-stripping machine, comprising in combination, a frame for holding a stack of press-plates and cakes wrapped in cloth between said plates, and mechanism for stripping the cloth and removing the plates.

50 9. An oil-meal-cake-stripping machine, comprising in combination with means for holding a stack of press-plates and cakes having cloth wrapped around the same, means for successively removing the plates and cakes from the stack and stripping the cloth.

55 10. An oil-meal-cake-stripping machine, comprising in combination, means for holding a stack of press-plates having cakes between them and cloth wrapped around the cakes, an ejector, mechanism for reciprocating said ejector to remove and strip said cakes from

said plates, and means for feeding said plates and cakes into the path of said ejector.

11. An oil-meal-cake-stripping machine, comprising in combination, an ejector, means for reciprocating said ejector, means for holding press-plates having cakes between them, and means for feeding the cakes and plates to said ejector.

70 12. An oil-meal-cake-stripping machine, consisting of mechanism for holding a series of plates and cakes having cloth wrapped around the same, an ejector by which the cakes are removed from the plates and the cloth stripped from the cakes, a plunger by which the press-plates are fed to the ejector, 75 a second plunger for receiving the press-plates from said ejector, means for operating said ejector and plungers, and take-up mechanism for the cloth as it is stripped from the cakes.

80 13. A machine for stripping oil-meal cakes, comprising in combination, mechanism L for holding a stack of press-plates having cakes between them and cloth wrapped around said cakes, press-plate-receiving mechanism M, 85 cloth-take-up mechanism E and ejecting mechanism D; whereby, as the ejecting mechanism operates, a cake is ejected from the plates, the cloth is stripped from said cake and wound, and the press-plate removed to 90 the receiving mechanism.

14. A machine for stripping oil-meal cakes, comprising in combination, a plunger for holding a series of press-plates having cakes between them and cloth wrapped around the cakes, a second plunger for receiving the press-plates, an ejector, drive mechanism by which the ejector is reciprocated above said plungers, a truck for receiving the press-plates from said second plunger, mechanism 100 for raising the first plunger and lowering the second plunger as the ejector operates, and take-up mechanism for the cloth; said ejector adapted to remove a cake from the first plunger and strip the cloth therefrom during its 105 forward movement and remove a press-plate to the receiving-plunger when returning.

15. In combination with a pair of plungers, one for holding a stack of cakes having press-plates between them and cloth wrapped 110 around said cakes, and the other for receiving the press-plates therefrom, mechanism for raising the first plunger and lowering the second plunger, means for ejecting the cakes and removing the plates onto the second 115 plunger and means for winding the cloth, and a truck adapted to receive the plates from the second plunger.

120 In testimony whereof I have signed my name to this specification in the presence of 125 two subscribing witnesses.

EDGAR C. BISBEE.
